UNITED STATES PATENT OFFICE.

CHARLES R. STEVENSON, OF MISHAWAKA, INDIANA, ASSIGNOR TO NATIONAL VENEER PRODUCTS COMPANY, OF MISHAWAKA, INDIANA, A CORPORATION OF INDIANA.

DESIGN FOR A GOLF-BAG.

49,101.

Specification for Design.

Patented May 23, 1916.

Application filed September 1, 1915. Serial No. 48,560. Term of patent 14 years.

To all whom it may concern:

Be it known that I, CHARLES R. STEVENSON, a citizen of the United States, residing at Mishawaka, in the county of St. Joseph and State of Indiana, have invented a new, original, and ornamental Design for a Golf-Bag, of which the following is a specification, reference being had to the accompanying drawing, forming part thereof.

The figure is a perspective of a rectangular golf bag in cross section showing my new design.

I claim:

The ornamental design for a golf bag, as shown.

CHARLES R. STEVENSON.

Witnesses:

MARIE PRAHL,

C. J. JOBSON.
